Inventor,

Milton F. Williams,
By G. C. Cornwall, Atty.

UNITED STATES PATENT OFFICE.

MILTON F. WILLIAMS, OF ST. LOUIS, MISSOURI, ASSIGNOR TO WILLIAMS PATENT CRUSHER AND PULVERIZER COMPANY, OF ST. LOUIS, MISSOURI, A CORPORATION OF MISSOURI.

CRUSHER.

1,122,453.

Specification of Letters Patent. Patented Dec. 29, 1914.

Application filed September 28, 1914. Serial No. 863,874.

To all whom it may concern:

Be it known that I, MILTON F. WILLIAMS, a citizen of the United States, residing at city of St. Louis, State of Missouri, have invented a certain new and useful Improvement in Crushers, of which the following is a full, clear, and exact description, such as will enable others skilled in the art to which it appertains to make and use the same, reference being had to the accompanying drawings, forming part of this specification, in which—

Figure 1 is a sectional elevation of a pulverizer containing my improvement. Fig. 2 is a detail illustrating a modified form.

My invention relates to certain improvements in rotary hammer mills which are used for reducing different materials. Its purpose is to increase the efficiency of the mill by securing more rapid reduction of the material, and to decrease the amount of power necessary to operate the mill. These results are obtained by providing the mill with a spirally formed cover portion which is equipped with auxiliary breaker or baffle plates, the cover and the plates being disposed so as to increase the effectiveness of the hammers upon partially reduced fragments of material and produce an arrangement whereby different fragments of the material act upon one another with a reducing effect.

By reference to the drawings, it will be understood that 1 represents the casing of a mill in which is mounted a cage or concave 2 and a rotary shaft 4 carrying pivoted beaters 5.

6 is a breaker plate disposed adjacent the feed opening 7, and 8 is a cover forming the upper portion of the grinding chamber. This cover 8 is of spiral form, the radial distance thereof from the shaft decreasing from the terminus adjacent the concave to the other terminus which is adjacent the feed opening. On this casing 8 are disposed transverse breaker plates 9 which extend across the casing in the longitudinal direction of the shaft 4. The breaker plates 9 may project radially toward the shaft or may project toward the shaft non-radially thereof. The width of the plates 9 is sufficient to extend to points adjacent the operating ends of the beaters when the machine is operated. Consequently, because of the spiral contour of the cover these breaker

plates will be of varying widths, the plate nearest the feed opening being the narrowest, and that nearest the concave 2 being the widest. This disposal of the breaker plates provides chambers 10 intermediate the breaker plates, which chambers vary in depth due to the spiral contour of the cover.

In the operation of the mill, material is fed into the feed opening and comes first into contact with the breaker plate 6 upon which it is partially broken by the action of the beaters into fragments of varying sizes. The material is then carried by the beaters over the concave 2 where it is to some extent reduced, the sufficiently small portions falling through the openings in the concave. Fragments of the material will be carried past the concave by the beaters and projected into the chambers 10. Lighter or smaller fragments will be carried farther around with the beaters than will the larger fragments. Consequently, the general run of material at a point just past the terminus of the concave will be larger than material at a point just ahead of the feed opening, and there will be less material carried to the chambers nearer the feed opening than to the chambers nearer the concave.

The spiral contour of the cover, wherein the chambers 10 are of different depths is for the purpose of securing a structure wherein the reducing action of the various fragments upon one another will be most effective. As the fragments are carried about by the beaters and projected into the chambers 10, they rebound from the auxiliary plates 9 and the cover 8 and work against one another continuously while they are in these chambers, due to the rapid action of the beaters 5. Due to the fact that the chamber nearest the concave is of the greatest depth, it is enabled to receive the comparatively large amount of material thrown into it, and give it the proper room for movement, while at the same time maintaining the coöperating surfaces in sufficiently close relationship to secure rapid action. Obviously, as the beaters move farther away from the concave, they will carry less of the material with them, and hence the chambers will receive less material according as they are farther from the concave. Due to the fact that they do receive such smaller quantities of material, these chambers are rendered more effective by decreas-

ing their depth, whereby to bring the co-operating surfaces into more intimate relationship, while at the same time allowing sufficient room for the manipulation of the material. Due to the fact that the chambers are thus arranged so that each is of the proper size to handle the amount of material projected into it, a very high efficiency is secured, and the amount of power required kept at a minimum.

I am aware that various changes and alterations can be made in my device, without departing from what I claim as my invention.

15 What I claim is:

1. The crusher or pulverizer comprising a casing having a feed opening, a breaker plate disposed below the feed opening, rotary beaters operating within the casing and 20 adapted to co-operate with the breaker plate, a concave disposed ahead of the breaker plate in the direction of movement of the beaters, the casing having a cover portion disposed spirally relative to the shaft, the 25 portion thereof adjacent the terminus of the concave being farther radially from the shaft than the said concave and the said cover portion spirally approaching the shaft in the direction of movement of the beaters, transverse breaker plates disposed on 30 said cover portion at intervals to form intermediate chambers, the respective breaker plates being of different widths and extending 35 from the casing to points adjacent the orbit of the operating ends of the beaters.

2. A rotary mill comprising in combination a grinding chamber having a foraminous cage portion and a cover portion and being provided with a feed opening, rotary beaters operating in said grinding cage, 40 a breaker plate disposed between said feed opening and said cage portion, said cover portion being disposed spirally relative to the orbit of the beaters, the distance between the casing and the operating ends of 45 the beaters decreasing in the direction of movement of the beaters, and a plurality of transversely disposed auxiliary breaker plates mounted on said cover portion and spaced apart from one another and extending 50 from the cover portion into proximity with the operating ends of the beaters.

3. In a crushing and pulverizing machine, the combination of a casing having a feed opening, a grinding surface, and a 55 spirally arranged cover having inwardly projecting portions forming chambers of different depths into which the material passing from the grinding surface is thrown by the action of the rotary beaters, the said 60 chambers decreasing in depth in the direction of movement of the beaters.

In testimony whereof I hereunto affix my signature in the presence of two witnesses, this 5th day of August 1914.

MILTON F. WILLIAMS.
